(57) **CLAIM**

The ornamental design for a connector accessory for toy robot, as shown and described.

DESCRIPTION

FIG. 1 is an isometric view, from the top left, of the connector accessory for toy robot;

FIG. 2 is an isometric view, from the bottom right, of the connector accessory for toy robot;

FIG. 3 is a left elevation view of the connector accessory for toy robot;

FIG. 4 is a top plan view of the connector accessory for toy robot;

FIG. 5 is a front elevation view of the connector accessory for toy robot;

FIG. 6 is a right elevation view of the connector accessory for toy robot;

FIG. 7 is a rear elevation view of the connector accessory for toy robot; and,

FIG. 8 is a bottom plan view of the connector accessory for toy robot.

The designations of the views below as top, bottom, right side, front, and rear are for ease of discussion only and are not intended to limit the connector accessory to one particular orientation. The drawings illustrated in FIGS. 1-8 are not necessarily drawn to the same scale, and any change in scale between different views is not intended to limit the connector accessory for toy robot to a particular size.

1 Claim, 3 Drawing Sheets
